UNITED STATES PATENT OFFICE.

PETER E. DE YOUNG COOK, OF BROOKLYN, NEW YORK.

DESIGN FOR A FLOWERPOT.

Application filed April 12, 1923. Serial No. 5,792. Term of patent 7 years.

To all whom it may concern:

Be it known that I, PETER E. DE YOUNG Cook, a citizen of the United States, residing in the city of New York, borough of Brooklyn, in the county of Kings and State of New York have invented a new, original, and ornamental Design for Flowerpots, of which the following is a specification, reference being had to the accompanying drawing, forming a part thereof.

I claim:

The ornamental design for a flowerpot, as shown.

PETER E. DE YOUNG COOK.
